DRAWER LOCKING MECHANISM

Charles M. Abrahamson, Aurora, Ill., assignor to
All-Steel Equipment Inc., a corporation of
Illinois

Application April 6, 1948, Serial No. 19,232

1 Claim. (Cl. 312—219)

1

This invention relates to mechanisms for locking desk drawers.

An important object of the invention is to provide novel drawer-locking means for desks.

Another object is to provide a desk having a novel locking mechanism which may be pre-set to lock the desk drawers.

A further object is to provide a pedestal type desk having unique drawer-locking means which may be readily installed in or detached from the desk.

An illustrative embodiment of my invention is shown in the accompanying drawings, wherein

Fig. 1 is an elevational view of the inner front portion of a left-hand desk pedestal in which the desk drawers are shown broken away in part;

Fig. 2 is a sectional view of part of the structure shown in Fig. 1, taken along the line 2—2, and showing a locking mechanism in its relationship to a desk drawer and to the knee-hole side member of a desk pedestal; and

Fig. 3 is a perspective of a portion of the structure shown in Figs. 1 and 2, and illustrating a locking mechanism in locked position with respect to a drawer slide and a drawer guide channel.

Considering the invention in its preferred form as applied to a pedestal type desk, Figs. 1 and 2 show a portion of a desk pedestal housing several drawers 11, each drawer being provided with slides 12 securely fastened to the sides thereof, and in slidable contact with and supported by drawer guide channels 13. Anti-friction rollers 14, suitably secured to a pedestal post 15, are provided to engage the bottom member of the drawer slides 12 to impart easier slidability thereto.

As shown in Fig. 2, the drawer slides 12 are attached to the sides of the drawers 11 by suitable means such as, for example, welding, as shown at 16, and the drawer guide channels 13 are rigidly secured to the pedestal corner post 15 (only one is shown) by means of tabs 17. As shown in Fig. 1, the tabs are an integral part of the drawer guide channels 13, extend into slots formed in the pedestal corner post 15, and are bent against the corner post sides to provide a firm connection.

While the drawings show the drawer slides 12, drawer guide channels 13 and rollers 14 as present in one side of the pedestal, it is understood, of course, that counterparts of these are suitably positioned in the other side of the pedestal, i. e., that part of the pedestal away from the knee-

10 hole. Also, while only one pedestal corner post 15 is shown, it is understood that there is preferably one such post at each corner of the pedestal and that the drawer guide channels 13 on each side of the drawers 11 are secured, as above described, to a front as well as to a rear pedestal corner post.

15 Referring now to the elements which are positioned in that part of the pedestal closest to the knee-hole side, as shown in Figs. 1 and 2, a latch bar 18 is separably connected to the drawer guides 13 by means of a shoulder bolt 19 which is rigidly secured to the latch bar 18, and which is inserted in a key hole slot 21 blanked out of the drawer guide channels 13, as shown in the drawings (particularly in Fig. 3). As readily seen from the drawings, the latch bar 18 is movable vertically and is prevented from lateral movement, except in its uppermost position, by means of the shoulder bolt connection with the drawer guide channels 13, as described above.

20 The latch bar 18 is provided with lugs or tongues 22 which are blanked out and offset as shown, and are positioned on the latch bar to coact with the drawer guides 13 and the drawer slides 12 in a manner described below.

25 The drawer guides 13 and drawer slides 12 are provided with slotted openings 23 and 24 respectively through their top flanges to receive the aforesaid latch bar tongues. When the latch bar 18 is in its lowermost position (best shown in Fig. 3), the latch bar tongues 22 pass through the aforesaid slots 23 and 24 in the drawer guide 30 channels 13 and the drawer slides 12 and engaging the forwardly facing shoulders or walls of the slots 24 to lock the drawers against outward movement. With the latch bar 18 in its uppermost position, as shown by the dotted portion of Fig. 2, the latch bar tongues 22 are above the aforesaid slots 23 and 24 and the drawer can be moved forwardly as desired.

35 The upward and downward movement of the latch bar 18 is effected by corresponding movements of a lock bolt 25, which is a part of a lock 26 and which effects contact with the bent-over portion of the latch bar as shown in Figs. 2 and 3. As shown in the drawings (particularly Fig. 3), movement of the lock bolt 25 upwardly and downwardly causes corresponding movement of the latch bar 18 and consequential engagement and disengagement of the latch bar 40 tongues 22 with the drawer slides 12 and the drawer guides 13.

45 In order to permit of pre-locking while one

2

or more drawers are extended, there is provided a spring 27 which is connected to and causes a downward pressure on the latch bar 18. The lower end of the spring 27 is held in a slot 28 of the spring-holding member 29 and the upper end of the spring is inserted in a slot 31 of the latch bar 18, the latch bar being bent as shown in Figs. 2 and 3. It is readily seen that when the drawers 11 are in an extended position and the latch bar tongues 22 are, therefore, not positioned within the slots 23 and 24 in the drawer slides 12 or the drawer guides 13, gravity and the tension on the latch bar 18 due to the spring 27 will cause the latch bar and the latch bar tongues 22 to move downwardly into the slots 23 and 24 when the drawers 11 are closed sufficiently to bring the slots 23 and 24 into alignment with the latch bar tongues 22. Obviously, the spring 27 may be omitted, if desired, relying on gravity alone for the downward movement.

An important feature of my invention is the positioning of the elements in the manner shown whereby the lock 26 is mounted on the inner side wall 32 of the pedestal and is operatively connected to a latch bar 18 which engages drawer slides 12 and drawer guide members 13 adjacent the knee-hole side of the desk. This is made possible by means of the offset structure of the latch bar 18 operating to engage the drawer slides 12 and the drawer guides 13 on the side of the drawer nearest the inner, or knee-hole, side of the pedestal. The lock 26 is a conventional type of lock having a key-operated bolt 25 which moves upwardly and downwardly, as hereinbefore described. The lock is secured to the inner side wall 32 of the pedestal in any suitable way.

After the latch mechanism is installed, the flange 33 of the spring-holding member 29 is bent from its dotted line position to its full line position (Figs. 1 and 2) to prevent accidental dislodging of the latch bar 18. This retains the latch bar in a position precluding entry of the shoulder bolts 19 into the circular top portions of the key hole slots 21. Obviously, the flange 33 may be bent upwardly to remove the latch bar when necessary or desirable.

Another important feature of my invention is the easy removability of the latch bar 18 from its shoulder bolt engagement with the drawer guides 13 for purposes of assembly and disassembly of the desk.

While I have shown and described an embodiment of my invention as part of the left-hand pedestal of a desk, the same general type of arrangement is, of course, contemplated for the right-hand side of a desk to provide a locking mechanism operatively connected to a lock which is mounted on the inner side wall of the right hand pedestal.

Although I have described a specific embodiment of my invention, it is understood, of course, that modifications thereof within the scope of my invention are possible to those skilled in the art, and that my invention is not to be limited except as required by the appended claim.

I claim:

In a desk or the like, a pedestal, a plurality of vertically spaced, horizontally slidable drawers mounted within the pedestal, each of said drawers having a forwardly facing shoulder projecting laterally from the drawer toward one side of the pedestal, a vertically movable latch bar adjacent said shoulders and slidably supported on the pedestal between said drawers and the adjacent portion of the pedestal, said latch bar being movable between an upper unlatched portion in which all drawers are free to move in and out of the pedestal to a lower latching position, means for biasing the latch bar to its lower position, a lock bolt engageable with the latch bar and adapted to positively lift the latch bar to its raised unlatched position, lugs carried by the latch bar for cooperation with said shoulders and adapted to latch said drawers against opening when all drawers have been closed, said lugs and shoulders also cooperating to permit all drawers to be closed after support of the latch bar in its raised position has been removed by retraction of the lock bolt.

CHARLES M. ABRAHAMSON.

Certificate of Correction

July 10, 1951

Patent No. 2,559,579

CHARLES M. ABRAHAMSON

It is hereby certified that error appears in the printed specification of the above numbered patent requiring correction as follows:

Column 4, line 28, before "position" insert *latching*;
and that the said Letters Patent should be read as corrected above, so that the same may conform to the record of the case in the Patent Office.

Signed and sealed this 25th day of September, A. D. 1951.
